NEEDLE HOLDING DENTAL TOOL

James B. Giern, Romeo, and John E. Bakke,
Detroit, Mich.

Application September 15, 1951, Serial No. 246,752

2 Claims. (Cl. 32—40)

1

This invention relates to dental tools and, in particular, to tools for use in the making of dental inlays.

In the making of dental inlays, wax impressions are made of a tooth cavity in order to ascertain the form of the cavity and prepare a cast which will accurately fit the cavity. In the making of the wax mold, it has been found convenient to insert phonograph needles in the wax impression or pattern while it is in the patient's mouth. Hitherto, the dentist has found difficulty not only in accurately inserting these needles in the wax impression while it is in the patient's mouth, but also in avoiding dropping needles into the patient's mouth. The present invention avoids these difficulties and enables the tiny wax pattern to be easily handled, either in removing it from the tooth cavity or in placing it in the mold for producing the metal cast on the bench.

One object of this invention is to provide a needle holder for dental inlay work which will firmly hold the needle while it is being positioned in the tooth cavity in the patient's mouth, but which will instantly release its grip on the needle after the needle has been imbedded to a sufficient depth in the wax impression or pattern.

Another object is to provide a needle holder for dental inlay work consisting of a handle having a chuck with openings for receiving the needle in various positions of use, and which contains a magnet yieldingly and releasably engaging the needle, so that when the needle has been inserted to a sufficient depth in the wax impression or pattern, the handle may be withdrawn, leaving the needle in position.

Another object is to provide a needle holder for dental inlay work of the foregoing character wherein the magnet is housed in a non-magnetic hollow head having openings therein at various angles permitting the rearward end of the needle to be inserted through one of the openings into magnetic contact with the magnet.

Other objects and advantages will become apparent during the course of the following description of the accompanying drawings, wherein:

Figure 1 is a side elevation of a needle holder for dental inlay impressions or patterns, according to one form of the invention;

Figure 2 is a central vertical section through the needle holder shown in Figure 1, with the magnet partly in side elevation;

Figure 3 is a bottom plan view of the needle holder shown in Figures 1 and 2; and

Figure 4 is a perspective view of the magnet of the tool, after removal of the tool.

2

Referring to the drawings in detail, Figures 1 and 2 show a needle holder for dental inlay impressions or patterns, generally designated 10, according to one form of the invention as consisting of a tubular handle 11 terminating in a head or chuck 12 containing a magnet 13. A plug 14 having a knurled portion 15 and a reduced diameter stem 16 is inserted into the upper end of the bore 17 of the handle 11, as by a press fit. The head or chuck 12 is elongated and roughly cup-shaped with a bore 18 receiving the magnet 13 and having a bottom wall 19 against which the lower end of the magnet 13 abuts. The upper end of the head or chuck 12 receives the lower end of the handle 11 by the press fit thereof in the bore 18 after the magnet 13 has been placed in position within the head 12. The lower end of the head 12 is preferably conical as at 20 and contains a longitudinal bore 21 and lateral bore 22 at right angles thereto for releasably receiving a phonograph needle N. An inclined bore 23 is also formed in the lower end of the head 12 and preferably intersects the bores 21 and 22. The bores 21, 22 and 23 are of such lengths as to open into the lower end of the bore 18 and come into contact with the lower end of the magnet 13. The magnet 13 is of an especially powerful type and is preferably of an aluminum, nickel and cobalt alloy.

In the use of the invention, the dentist inserts a needle end in one of the three bores 21, 22 or 23 in the head or chuck 12 until the blunt end thereof engages the powerful magnet 13. The latter then holds the needle firmly in position while it is being inserted in the wax impression or pattern in the tooth cavity in the patient's mouth.

The dentist then carefully withdraws the tool from the patient's mouth, leaving the needle embedded in the mold, since the frictional engagement of the wax of the impression or pattern on the pointed part of the needle N exceeds the magnetic force tending to hold the needle in its respective bore 21, 22 or 23. In this manner, any desired number of needles can be inserted to any desired depth and at any desired angle, depending upon which of the bores 21, 22 and 23 is used to hold the needle.

The needles N thus remain fixed in the wax impression or pattern, so that the pattern can then be withdrawn from the tooth cavity and invested in the conventional manner well known to those skilled in the dental art.

What we claim is:

1. A dental tool for temporarily and releasably holding a steel phonograph needle or the like,

said tool comprising an elongated head having an elongated socket therein closed at one end by an end wall, said end wall having a needle-holding bore therethrough extending into said socket, said bore being of substantially the same size and shape as the shank of said needle whereby to rigidly but releasably hold said needle in said head, a magnet disposed in said socket having one end disposed adjacent said end wall and yieldably and releasably engageable with said needle seated in said bore, and an elongated handle having one end seated in said socket in retaining engagement with said magnet.

2. A dental tool for temporarily and releasably holding a steel phonograph needle or the like, said tool comprising an elongated head having an elongated socket therein closed at one end by an end wall, said end wall having a plurality of needle-holding bores therethrough extending into said socket, said bores being disposed at dif-

5

10

ferent angles relatively to the axis of said head, said bores being of substantially the same size and shape as the shank of said needle whereby to rigidly but releasably hold said needle in said head, a magnet disposed in said socket having one end disposed adjacent said end wall and yieldably and releasably engageable with said needle seated in said bore, and an elongated handle having one end seated in said socket in retaining engagement with said magnet.
